UNITED STATES PATENT OFFICE

FRANK W. TRABOLD, OF DETROIT, MICHIGAN

FOOT PEDAL

Application filed March 26, 1930. Serial No. 438,961.

This invention aims at the construction of foot pedals so formed and disposed as to obviate unfavorable effects, or to produce favorable effects, upon the feet of the user.

Recognized benefits being derivable from various forms of so-called arch supports, used in shoes, or from certain exercises for the correction of arch troubles, this invention aims at obtaining somewhat similar or equivalent effects or preventing such troubles, incidentally to the operation of machinery or to the driving of a car; and, in various embodiments, a treadle for two feet or either or both of a pair of pedals (such as a clutch pedal and a brake pedal) may be originally formed or subsequently shaped or equipped to provide means tending toward what may be referred to as an arch-elevating effect and/or an in-toeing effect upon the feet of the user. The intended result, in any case, is a favorable angular relationship of the respective parts of the feet and limbs of the user and a favorable disposition of pressures and tensions thereon and therein.

Other objects of the present invention may be best appreciated from the following descriptions of illustrative embodiments thereof, taken in connection with the appended claim and the accompanying drawings.

Fig. 1 is a diagrammatic forward-looking view in which a pair of pedals originally constructed in accord with this invention are shown in vertical section,—intended relationships thereof to the shoes or feet and limbs of a user being also indicated.

Figs. 2 and 3 are diagrammatic smaller views, comparable with the left hand portion of Fig. 1, showing alternative forms in which portions of foot-receiving members are elevated in general accord with the principles of this invention.

Fig. 4, taken similarly to Figs. 2 and 3, suggests another form, in which the desired inclination is obtained by providing a lateral bend in a motion-transmitting member.

Figs. 5-7, inclusive, taken similarly, suggest alternative devices by which a pedal

not originally embodying this invention may be modified or equipped in accord therewith.

Fig. 8 is a top plan view illustrating a toe-inturning feature that may be used in connection with any of the forms shown in previous figures or independently thereof.

Fig. 9 is a sectional view, with a slight perspective effect, showing an embodiment of the invention as incorporated in a treadle, for operation by two feet.

Fig. 10 is a view comparable with preceding figures but showing a form in which various features thereof are combined and associated with additional features.

Figs. 11 and 12 are elevational views showing alternative details as to methods of interconnecting pressure-receiving members with motion transmitting members.

Figs. 13 and 14 are diagrammatic views suggesting inclinations of pairs of pressure-receiving members, different from that shown in Fig. 1,—use of threaded angle-varying elements without plates being shown in Fig. 14.

Fig. 15 is a view taken similarly to Fig. 1, etc., but showing a form in which special provision is made for adjustably varying the lateral tilt of the pressure-receiving pedal plate.

Fig. 16 is a sectional view taken substantially as suggested by the line 16-16 of Fig. 15.

Fig. 17 is taken similarly to Fig. 16.

Referring first to Fig. 1, a pedal for either foot may include, in addition to a foot-receiving member or plate 10, preferably provided at its outer or lower edge with a flange 11, a separate or integral and deflected or straight motion-transmitting member 12. This pedal may operate a clutch in a usual manner; and a motion-transmitting member 12', shown as oppositely inclined to the clutch operating member 12 (and presumably serving to apply a brake) may be either integrally or separably connected with parts analogous to those above mentioned,—the members 10' and 12' being shown as interconnected by means of a bolt or rivet 13', extending through lugs 14' and corresponding

characters being applied thereto with the addition of a "prime" mark. In order more clearly to indicate the resultant positions of the feet of the user, shoe soles, engaging transversely inclined pressure-receiving areas, are indicated at 15, 15' and shoe toes at 16, 16',—axes of the user's respective legs being indicated by lines 17, 17' and the intended angle at the ankle joints being indicated diagrammatically by intersections of the lines 17, 17' with lines 18, 18'.

In Fig. 2 it is suggested that, even though a motion-transmitting member 12a be vertically disposed and connected with a foot-receiving member 10a by a horizontal member 13a, an effect similar to that above described may be obtained by cupping or upwardly bending the inner edge portion 19a of member 10a in such manner as to give an outward tilt to the sole 15a of a user's shoe; and Fig. 3 suggests that a similar effect may be obtained by producing an off-set or stepped effect, as at 19b.

Fig. 4 aims to suggest the transformation of an originally horizontal pedal including a foot-receiving member 10c and a motion-transmitting member 12c into an embodiment of the present invention by providing a suitable bend, as at 20c, in the member 12c; and Figs. 5-7, inclusive, will be seen to aim at alternative solutions of the problem of adapting ordinary pedals to produce the beneficial effects toward which the present invention is directed.

In Fig. 5, an originally flat foot-receiving member 10d is shown as built up or supplemented by an inclined surface element or insert in the form of a plate 21d,—this being elevated, at its inner edge, to provide an inclined pressure-receiving area, by means such as a rivet or bolt 22d including a head 23d and optionally secured by means such as a removable nut 24d upon a threaded portion 25d thereof. It will be seen that this construction permits a head 23d of any desired thickness to be employed, and that it also permits the removal of some or all of the mentioned parts and their re-insertion at will, in accordance with the preferences of successive users.

In Fig. 6, it is suggested that, to solve substantially the same problem as above referred to, a foot-receiving member 10e be provided with an inclined-surface element in the form of a wedge-shaped removable insert 21e, the inner edge thereof being given any thickness suitable to provide an area at the required inclination and said insert being retained by any suitable means,—such as a downwardly and inwardly re-curved extension 26e, secured by means of a screw 22e, or its equivalent; and in Fig. 7, a foot-receiving member 10f is shown as having disposed therein a plate 21f whose elevation is adjustable by means of a wing-screw 22f,—such as

may be threaded into a member 10f and locked in any adjusted position by means of a nut 24f.

In Fig. 8, an advantageous feature which may be employed in connection with any of the described embodiments of the present invention or independently thereof is separately illustrated. Although a receiving member 10g, for the left foot, is shown as having a slightly different general configuration from a receiving member 10g' for the right foot, the point aimed at, in the constructions here referred to, is such a form and angular disposition of any flanges, such as those shown at 11—11f in the mentioned figures and at 11g, 11g' in the Fig. 8, as not only to retain the feet on the pedals but to produce a toe-inturning or pigeon-toe effect, substantially as suggested by the outlines of shoesoles at 15g, 15g'.

In Fig. 9, a foot-receiving element in the form of a treadle 10h, which may be viewed as a pair of pedals united, of such form and dimensions as to adapt it favorably to receive both feet of the user, is shown as centrally "crowned" at 19h, and as provided with lateral flanges 11h and 11h',—the structure here referred to being obviously suitable for use upon a sewing machine, or the like, and obviously effective toward the same results as are obtained by constructions previously described.

By way of emphasizing the fact that various features shown in mentioned figures may be conjointly used, with or without additional features, a motion transmitting member 12i is shown in Fig. 10 as provided with such a bend at 20i as to produce a slight outward inclination in a foot-receiving member 10i, and means for varying the angle of inclination of the user's foot are shown as including not only a wedge-shaped element 21i, but also an inclined plate 21i'. This plate, if used, may be provided with numerous openings 27i through which may project extensions from the wedge-shaped member 21i,—which may be formed of a rubber-like or other friction-assuring composition. In this form, an upwardly bent or curved tongue 28i is shown as extending through an opening 29i in a flange 11i; and an assembly including either or both of the elements 21i and 21i' may be retained by means such as a bifurcate or other downwardly and inwardly re-curved extension 26i,—shown as slotted at 30i to receive a wing screw 31i. This screw may extend through a threaded boss 32i,—optionally forming a depression in the member 10i; and it may be provided not only with a swivel-connected plate 33i, receivable in said depression, but with a lock nut 24i,—the swivel-connected plate to 33i being shown as engaging an inner plate 34i, integral with the mentioned plate 21i.

In Fig. 11, a motion-transmitting lever 12*j*, disposed in a substantially vertical plane, is shown as connected with an inclined plate 10*j* by means comprising a correspondingly inclined bolt, screw or rivet 13*j*,—extending through a pair of lugs 14*j*, 14*j'*; and the construction shown in Fig. 12 is similar except that a shorter cylindrical element 13*k*, as used to connect the members 10*k* and 12*k*, extends through but a single lug 14*k*.

Figs. 13 and 14 are added to emphasize the fact that, as deformity or special needs of a particular user may dictate, pedal plates 15 may be either inwardly or outwardly inclined; and flanges 11*l*, 11*l'* are shown as disposed at the inner edges of plates 10*l*, 10*l'*, intended to receive respectively a left foot and a right foot. It being assumed that 20 the feet of the user of the pedals shown in Fig. 14 require plates 10*m*, 10*m'* both to be inclined downward toward the lifts, stops 11*m*, 11*m'* are provided at the lower edges thereof; and Fig. 14 incidentally emphasizes the fact that headed elements, such as 25 rivets, screws or bolts 22*m*, 22*m'* adjacent an edge of a pedal, may be used, even without additional inserted elements, directly to impart a desired inclination to the foot of 30 the user.

Finally, Figs. 15 and 16 will be seen to suggest the use of means whereby the transverse inclination of a pressure-receiving member in the form of a plate 10*n* may be 35 adjustably varied, relatively to a motion-transmitting member 12*n* for any desired arch adjusting effect. For this purpose, a bolt 13*n*, extending through a single transverse lug 14*n* on the member 10*n* and 40 through two parallel terminal members 12*n'* and 12*n''* on the lever 12*n* is shown as provided with a plurality of nuts 35*n*, 36*n*,

the latter being a lock nut; and the construction shown in Fig. 17 will be seen to resemble that of Fig. 16 except as it suggests the use of but one terminal member 12*p'* on the lever 12*p*, to cooperate with a lug 70 14*p* on plate 10*p*,—serrated contact surfaces being provided upon the parts last referred to and one or more nuts 35*p*, 36*p* being used on bolt 13*p*.

The structure, function and general mode of use of pedals of the described novel type having been fully indicated above, it may be emphasized, in conclusion, not only that various features of the present invention might be independently employed but also that numerous modifications, additional to the many suggested herein and adapting the invention to economical manufacture or to use either upon machines for industrial use to use upon regular bicycles, exercising bicycles, rowing machines or elsewhere, or might easily be devised by skilled workers if informed of the foregoing,—all without departure from the scope of the present invention as the latter is indicated in the 90 accompanying claim:

I claim:

A foot pedal organization for use in the operation of the brakes and clutches of automobiles comprising a motion transmitting member, a foot receiving member integral therewith and provided with a pressure receiving area, which is transversely inclined, said foot receiving member being provided adjacent the outer edge thereof with an upwardly extending curved flange portion, for providing an in-toeing effect, and means operatively connected to the foot receiving member, for adjustably varying the inclination of the pressure receiving area. 100 105
